S. GUBITOSI

SHOE HEEL ATTACHING APPARATUS

Filed Jan. 27, 1927

INVENTOR
Sabino Gubitosi
BY
Warren E. Willis
ATTORNEY

UNITED STATES PATENT OFFICE.

SABINO GUBITOSI, OF BROOKLYN, NEW YORK.

SHOE-HEEL-ATTACHING APPARATUS.

Application filed January 27, 1927. Serial No. 163,940.

This invention relates to apparatus used in the construction of shoes and more particularly to devices facilitating attachment of the heel portions to their bodies, with special respect to types of high heels as used in connection with women's shoes.

Such heels are ordinarily composed of wood, metal or similar substances, shaped appropriately and secured to the shoe sole rigidly, the heel being covered with leather or finished in colors corresponding to the shoe.

Obviously the upper portion of the heel must closely match the profile of the sole at the point of attachment so that their edges blend nicely and must be held securely in position, preferably when the shoe is on a last to avoid distortion.

It is therefore an object to provide an adjustable clamp whereby the heel may be firmly pressed against the sole of a shoe containing a last, means also being provided to engage the last by the opposite end of the clamp, the same having means which permit of adjustment.

It is a further feature to provide the lasts with a passage through which a screw, nail or the like may be entered and driven through the sole into the heel when clamped thereagainst in a properly adjusted position.

Another purpose is in the provision of means to facilitate securing of the heel facing, the same being a strip of thin leather disposed under the instep portion of the sole and front of the heel.

A further object is to so arrange the clamping device as to support the shoe in either of two adjusted positions in which the different operations are performed, the clamp supports being carried on a type of track permitting a plurality of shoes to be operated upon consecutively and without waste of valuable space.

These several objects, together with others of advantageous nature, which will be understood as the description proceeds, are accomplished by the novel construction and combination of parts hereinafter described and shown in the accompanying drawing, forming a material part of this disclosure, and in which:

Figure 1 is a top plan view of an embodiment of the invention illustrating its application.

Figure 2 is a side elevational view of the

same, partially in section and parts broken away to disclose the construction.

Figure 3 is a sectional view looking on line 3—3 of Figure 1.

Figure 4 is a fragmentary side view similar to Figure 2 but showing a modified form of structure.

In the drawing, the numeral 10 generally designates a rail of rectangular cross-section and of indefinite length provided with a plurality of spaced support brackets 11 fixed to a wall.

Manually movable on the rail 10 are a plurality of slides 12 open at the top to permit passing the brackets 11, the lower portion of each slide having a transverse bore in which is rotatable a spindle 14 having a head at one end, the other end anchoring in a clamp frame.

The frame consists of an upwardly extending arm 20 having a goose neck 21 its lower extremity having hinged to it at 22, an offset plate 23 adapted to engage the upper rear surface of a last 24 contained in a shoe 25, the plate being so mounted to allow for the angular differences in the top faces of various lasts.

The plate 23 is adjusted into operative position by a set screw 26 passing through a lug 27 extending from the end of the neck 21, and is provided with a central opening 28.

The frame further consists of a downwardly extending arm 30, having a rib 31 on one side and carries at its lower end a lug 32 through which passes a clamp screw 33, having a head, the point of the screw engaging a heel plate 35 slidable on the arm 30, but prevented from turning by reason of abutting the rib 31, the upper surface of the plate being bevelled to support the shoe heel 37 to be applied to the shoe 25.

The central portion of the clamp frame contains a recess closed by a plug at one end, against which abuts a coil spring 38 pressing a detent pin 39 normally outward to engage a depression 40 in the slide 12 when the frame is in a vertical position and a corresponding depression 40' when the same is in a horizontal position, the rotating movement being limited by stops 41 extending from the slide.

Formed on the frame above the rib 31, is a pair of spaced, undercut, horizontal ribs 54 in which is movable a slide 55 adjustable

by a set screw 56, the slide carrying at its outer end a guide 57 to abut the rear of the shoe to properly align the heel with the same.

6 Thus by placing the last 24 in the shoe and clamping the plate 23 against the upper surface of the last, the plate 35 against the heel 37, and the guide 57 against the rear of the shoe, the same will be held in a positive and rigid manner, while a screw is inserted through the opening 28 and last 24, so that the same may be engaged into the heel 37.

15 In applying the heel facing, a thin piece of leather 43 is coated on the inside with cement, and placed under the instep, in front of the heel of the shoe and is held there for drying by elastic straps 44 having hooks engaging button heads 45 fastened to the back of the frame, the free ends 20 passing tightly around the facing 43.

25 In the modification shown in Figure 4, the facing 43 is attached to the instep and front of the heel as before, but instead of using the straps 44, it is held in place by a soft rubber cushion 50 rotatable in an angular extension 53 formed on the plate lug 32.

30 Thus, it may be seen that a clamp has been disclosed having means for positively and rigidly holding a shoe mounted on a last, while a heel is being attached thereon.

35 It may also be seen that the device embodies an advantageous method of securing the heel and is capable of adjustment to comply with convenient handling of the operator.

40 While certain preferred embodiments of this device have been shown and described, it will be understood that changes in the form, arrangements, proportions, sizes and details thereof may be made without departing from the scope of the invention as defined in the appended claims.

45 Having thus described my invention, what I claim as new and desire to secure by Letters Patent, is:—

50 1. A shoe heel clamp comprising a support rail, an encompassing slide movable on said rail, a frame pivoted in said slide, and means on said frame to clamp a shoe heel to a shoe.

55 2. A shoe heel clamp comprising a support rail, an encompassing slide movable on said rail, a frame pivoted in said slide, arms on said frame, means on one of said arms to support a shoe heel, and means on the other arm to engage a last contained in a shoe so that the shoe and heel are brought into rigid juxtaposition, both of said means 60 being offset laterally from said arms.

65 3. A shoe heel clamp comprising a support rail of rectangular cross section, a slide

movable on said rail and positively engaged thereto, a frame pivoted in said slide, means intermediate said frame and said slide to 65 adjust the angular position of said frame relative to its axis, a plate pivoted at its front edge on said frame, said plate extending laterally, means on said frame to adjustably secure said plate against a last contained in a shoe, and means on said frame to clamp a heel on the shoe.

70 4. A shoe heel clamp comprising a support rail of rectangular cross section, a slide movable on said rail and positively engaged 75 thereto, stops on said slide, said slide containing spaced depressions, a frame pivoted in said slide, a spring pressed detent on said frame to engage in the mentioned depressions to adjust said frame in various angular positions, an adjustable clamp on said frame to engage a last enclosed in a shoe, and adjustable means on said frame opposite said clamp to engage the heel of said shoe.

75 5. A shoe heel clamp comprising a rail, a carriage slidable on said rail, a frame pivoted in said carriage, means intermediate said frame and carriage to adjust the angular position of said frame relative to its axis, a pair of arms on said frame, an adjustable clamp on one of said arms, a plate slidable on the other arm, and means on said last named arm to adjust said plate, said plate and clamp being laterally offset and in register.

80 6. A shoe heel clamp comprising a rail, a carriage slidable on said rail, a frame pivoted in said carriage, stops on said carriage, said stops limiting the rotation of said frame, and means adjustable on said frame to clamp a heel to a shoe thereon.

85 7. A shoe heel clamp comprising a rail, a carriage slidable on said rail, a frame pivoted in said carriage, adjustable clamps on said frame to engage a shoe having a facing 90 for the heel, and adjustable means on said frame to hold said facing against said heel.

95 8. A shoe heel clamp comprising a rail, a carriage slidable on said rail, a frame pivoted in said carriage, adjustable clamps on said frame to engage a shoe, and means on said frame to guide said shoe and the heel thereof in line with each other.

100 9. A shoe heel clamp comprising a rail, a carriage slidable on said rail, a frame pivoted in said carriage, adjustable clamps on said frame to engage a shoe, a pair of undercut ribs on said frame, an adjustable slide in said ribs and a guide on said slide to abut the rear of said shoe.

105 Signed at Brooklyn in the county of Kings and State of New York this 11th day of January, A. D. 1927.

SABINO GUBITOSI,
